UNITED STATES PATENT OFFICE

2,358,731

THREAD-END CLAMPING DEVICE

Charles U. Olson, Evanston, Ill.

Application June 5, 1942, Serial No. 445,878

2 Claims. (Cl. 112—253)

The present invention relates to a thread-end clamping device adapted for use in connection with a sewing machine whereby unintentional withdrawal of the thread end from the eye of the needle due to accidental movement of the thread in a direction away from the needle may be effectively controlled without impairing the free feeding of the thread to the needle as required by the sewing operation.

It is a further object of this invention to provide an attachment of this character adapted to accommodate itself to the vibration of the sewing machine frame to which it is secured, without sacrificing its efficiency to positively clamp or release the thread as desired.

With the above and other objects in view, as will be apparent, this invention consists in the construction, combination and arrangement of parts, all as hereinafter more fully described, claimed and illustrated in the accompanying drawing:

Fig. 1 is a fragmentary elevation showing the present thread end clamping attachment in operative position on the frame of a conventional sewing machine; in the full lines the presser foot and presser foot lever are shown with the parts positioned as when in thread-clamping position and in dotted lines with the parts positioned as when in thread-releasing position.

Fig. 2 is an enlarged detail view of the present attachment showing the position of the parts when the same are in thread gripping position.

Fig. 3 is a similar view showing the position of parts when the thread is in released relation and being fed to the needle during sewing.

Fig. 4 is a sectional view on line 4—4 of Fig. 1.

Fig. 5 is a detail view taken on line 5—5 of Fig. 4.

The thread-end clamping mechanism contemplated by this invention is preferably mounted on the sewing machine head portion or frame in which the needle mechanism and the presser foot shaft operates.

Reference being had more particularly to the drawing, 10 designates a supporting member or plate having an opening near an edge thereof through which the member 10 may be attached to the side of the sewing machine head by the usual screw fastening at the lower limits of a plate usually employed to enclose the needle and presser foot mechanism in the machine head. The upper portion of the plate 10 is preferably offset outwardly of its lower portion so as to permit disposal of the upper portion of the plate 10 on the machine head plate 11 above the shoul-

der at the lower limits of said plate 11 and yet dispose the lower part of the plate 10 in a vertical plane in proximity to the path of movement of the needle 18.

Secured to the plate 10 are a pair of eyes 15 and 16 through which the thread 17 is arranged to travel lengthwise of the plate 10 in a path oblique to the path of the needle 18. Intermediate the eyes 15 and 16 is a cylindrical member 10 23 mounted for rotation about a pivot 24 about which the thread 17 is adapted to be drawn and bent in its path between said eyes 15 and 16. The thread 17 is preferably arranged to contact the surface of the member 23 through an arc of substantially 180 degrees by means of a bearing or cylindrical member 20 projecting from the plate 10 just below the limits of the upper portion of the plate 10 and a similar bearing 20 projecting from the plate 10 just below the cylindrical member 23. The member 23 is so arranged with respect to the pivot 24 that its center of gravity is below the pivot 24 whereby the member 23 is adapted to rotate by gravity toward a position in contact with the portion of the thread 17 in engagement with the bearing 21 therebelow. Accordingly, movement of the thread 17 in a direction away from the needle 18 will cause the thread 17 to exert sufficient frictional contact with the member 23 as to tend to drive the member 23 into closer clamping engagement with the thread 17 engaging the bearing 21, to positively limit further movement of the thread 17 in a direction away from the needle 18.

Operation of the member 23 in a direction 35 away from the thread 17 engaging the bearing 21 to permit release of the thread 17 for movement toward the needle 18 is brought about upon initial movement of the thread 17 in a corresponding direction due to the frictional contact 40 provided between the thread 17 and the member 23 which tends to drive the latter in a movement away from the bearing 21.

Due to vibration set up in the frame of the sewing machine during sewing whereby unintentional movement of the member 23 into clamping engagement with the thread 17 sometimes occurs, it is desirable to provide means for positively maintaining the member 23 in a position clear of the bearing 21 during sewing operations. 50 To this end the plate 10 is provided with a slot 32 in which a pin 31 projecting from the bearing or member 23 is adapted to establish limits for rocking movement of the member 23. The pin 31 is so extended as to intersect the path of a 55 lever 30 mounted for pivotal movement on the

reverse side of the plate 10 whereby the lever 30 may be operated to raise and hold the pin 31 in a limited position with respect to the slot aforesaid and thereby maintain the member 23 away from the bearing 21. Operation of the lever 30 is obtained through a leaf spring 35 anchored to the lever 30 and preferably projecting laterally into the path of a suitable lug or projection carried by the presser foot bar of the sewing machine. As shown in the drawing, the lug may take the form of a conventional cutter blade 36 mounted for adjustment on the presser foot bar. Thus when the presser foot is in idle or raised position the blade 36 is lifted to a position clear of the leaf spring 35 so as to permit the member 23 to operate by gravity to assume a thread clamping position, and when the blade 36 is lowered through lowering of the presser foot shaft and presser foot into operative or sewing position, the blade 36 engages the spring 35 to resiliently hold the pin 31 against the edge of the slot to limit or bias the member 23 into a position clear from the bearing 21 so as to release the thread 17 for movement toward the needle 18.

The arcuate thread engaging surfaces of the members 21, 22 and 23 are advantageous to the efficient operation of a thread end clamping device as contemplated by this invention since it prevents localization of strain on the strand of thread 17. However, the present invention is not limited to the specific embodiment herein shown and described but is capable of many variations and applications without departing from its spirit and scope as set forth in the appended claims.

What is claimed is:

1. In a thread-end clamping device adapted for attachment to the frame of a sewing machine,

a supporting member, means associated with said supporting member through which a strand of thread is trained to travel in a predetermined path including a bearing presenting a thread-engaging surface of convex cross-sectional contour, means cooperating with the thread portion in engagement with said bearing to prevent movement of the thread in a direction away from a needle associated with said machine including

10 a member pivotally mounted on said support for movement on said support toward and away from said bearing and about which said thread strand has contact throughout an arc of substantially 180 degrees, and means through which said member is biased to a position away from said bearing including a resilient lever adapted to contact with a projection on the presser foot shaft of said machine when the presser foot is in work position.

20 15 25 30 35 2. In a thread-end clamping device adapted for attachment to the frame of a sewing machine, a supporting member, means associated with said supporting member through which a strand of thread is trained to travel in a predetermined path including a bearing presenting a thread engaging surface of convex cross-sectional contour, means cooperating with the thread portion in engagement with said bearing to prevent movement in a direction away from a needle associated with said machine including a cylindrical member mounted for pivotal movement on said support toward and away from said bearing and biased by gravity for movement toward said bearing, and means actuated by the presser foot control associated with said machine for effecting movement of said cylindrical member away from said bearing.

CHARLES U. OLSON.
